UNITED STATES PATENT OFFICE

112,009

DESIGN FOR A SHOE OR SIMILAR ARTICLE

Margurite Ullman, New York, N. Y.

Application August 6, 1938, Serial No. 79,149

Term of patent 3½ years

To all whom it may concern:

Be it known that Margurite Ullman, a citizen of the United States of America, residing in the city of New York, county of New York, and State of New York, have invented a new, original, and ornamental Design for a Shoe or Similar Article, of which the following is a specification, reference being had to the accompanying drawing, forming part thereof.

Fig. 1 is a perspective view of a shoe or similar article showing my new design.

Fig. 2 is a fragmentary view of a portion of the vamp.

The essential features of my design are the series of cable stitches in diamond formation connecting the slitted portions of the shoe.

I claim:

The ornamental design for a shoe or similar article, substantially as shown and described.

MARGURITE ULLMAN.
